UNITED STATES PATENT OFFICE.

MONTROSE P. McARDLE, OF ST. LOUIS, MISSOURI, ASSIGNOR TO HYDRAULIC PRESS BRICK COMPANY, OF ST. LOUIS, MISSOURI, A CORPORATION.

DESIGN FOR A WINDOW-SILL.

No. 39,205.

Specification for Design.

Patented March 17, 1908.

Application filed September 3, 1907. Serial No. 391,275. Term of patent 3½ years.

To all whom it may concern:

Be it known that I, MONTROSE P. McARDLE, a citizen of the United States of America, residing in the city of St. Louis and State of Missouri, have invented a new, original, and ornamental Design for Window-Sills, of which the following is a specification, reference being had to the accompanying drawing, forming part thereof.

The figure is a perspective view of a window-sill showing my new design.

I claim:

The ornamental design for a window-sill as shown.

MONTROSE P. McARDLE.

In presence of—

BLANCHE HOGAN,
Wm. H. SCOTT.
